INTERPOLATING RECEIVING SYSTEM

William A. Knoop, Hempstead, N. Y., assignor
to Bell Telephone Laboratories, Incorporated,
New York, N. Y., a corporation of New York

Application May 13, 1929, Serial No. 362,781

41 Claims. (Cl. 178—88)

This invention relates to high speed synchronous telegraph systems in which, due to the characteristics of the transmission line, short signal impulses are excessively attenuated and must be 5 rebuilt at the receiving end or the relaying point. Heretofore receiving systems for this purpose have been commonly termed vibrating relay systems. This expression is somewhat misdescriptive of the system of this invention (because short impulses 10 are rebuilt without vibration of any relay) and therefore, in this specification the expression "interpolating receiving system" will be used to define a system which restores, or interpolates short signal impulses which have been attenuated to 15 such an extent that they are incapable of controlling a receiving relay or a relay for retransmitting the impulses into the next line section.

As the speed of transmission over a submarine cable or a long transmission line is increased the 20 single impulses of dot length, whether positive or negative polarity, often become so attenuated, that is so reduced in strength and distorted or altered in wave shape form by the transmitting medium, that with the customary voltages applied, perfect reception at high speed is difficult. This condition also exists in signals of a length 25 greater than the single or dot impulse in that the beginning of the impulse is attenuated so that the first part of the signal which corresponds 30 to the first part of the combination is not correctly received.

The effect of such distortion and loss of energy is considerably minimized by the use of the Gulstad relay which comprises a three winding polarized relay. The usual Gulstad relay is provided 35 with a line winding, an opposing winding, and an accelerating winding, the latter two being locally operated. By proper local circuit arrangements, including condensers and resistances, the 40 current flowing through one of the local windings operates the relay armature to its opposite contact, which thereupon closes a circuit so that current of reverse polarity flows through the winding and the armature is moved back to its original position. If the armature vibrates between its 45 contacts in synchronism with the transmission of the signals, the effect on the local apparatus is the same as if impulses of periodically reversed polarity were being received. In this manner attenuated impulses, although too weak to operate 50 the line relay armature, are not lost. By adjusting the resistances and condensers in the local circuits, the relay tongue can be arranged to vibrate between its armature contacts at any desired frequency. However, considerable difficulty

is experienced with this relay system due to the fact that no means is provided for insuring absolute synchronism between the vibration of the armature and the received signaling impulses. Considerable difficulty is also experienced due to the fact that the vibration causes continuous wear of the armature contacts. 5

Attempts to overcome the difficulties disclosed in the Gulstad relays were made in the systems disclosed in patents granted to A. A. Clokey, 10 Nos. 1,522,865 of January 13, 1925 and 1,521,870 of January 6, 1925. In these two patents, distributors are disclosed which rotate at the proper speed for maintaining the vibration of the armature of the relay operating as a Gulstad relay in synchronism with the received impulses. The resistances and condensers of the Gulstad system are replaced partially by distributors which control the speed of relay operation. Here again, however, the armature of the relay vibrates continually and there is therefore the same drawback of wear on the armature. 15 20 25

The present invention provides arrangements for operating electro-responsive devices of the Gulstad relay type in such a manner that there is normally no wear on the armature part and the operation is automatically maintained in synchronism with the signal impulses. 25

This invention also provides for operating electro-responsive devices in a similar manner to that of the Gulstad relay, but avoids any moving or vibrating parts operating at the speed of unit signal impulses, thus eliminating failures from this source on high speed circuits. 30

An object of the invention is to greatly increase 35 the speed of interpolating receiving systems without sacrifice of accuracy and reliability.

Another object of this invention is to provide means for repeating attenuated signaling impulses by electromagnetic means arranged in such 40 circuits that their armatures do not vibrate while signals are not being received.

Still another object of this invention is to provide means whereby the printer selecting magnets may be energized to operate them for a greater 45 percentage of the signal period than could normally be obtained under the Gulstad relay system.

Heretofore, as noted above, it has been a practice to rebuild or restore short impulses at the 50 receiving station by means of relay systems in which a relay vibrates under the control of special distributor segments to automatically restore signal impulses of unit length. Such vibrating relay systems have rather definite speed limita- 55

tions and long loaded telegraph cables are now in existence which have a possible speed of transmission exceeding that at which they are capable of operating satisfactorily.

- 5 The present invention is exemplified by an embodiment in which a three-position line relay or mixing relay controls the impulses which two halving relays, each controlling the other, transmit to each other, in accordance with line impulses 10 whereby line impulses acting through the line or mixing relay cause the two relays to transmit to the printer magnets or retransmitting relays impulses coming in from the line. When the line relay is uncontrolled by incoming impulses 15 and stands in its mid-position the two halving relays each assumes opposite positions and relay to the printer magnets or retransmitting relays properly timed and phased unit impulses.

20 Fig. 1 is a circuit diagram, with developed distributors, of a circuit in accordance with the invention;

Fig. 2 is a series of graphs explanatory of the operative action of the parts of Fig. 1;

25 Fig. 3 is a circuit diagram of a modified form using a single printer magnet; and

Fig. 4 is a circuit diagram of a further modified circuit.

Description of circuit of Fig. 1

30 A cable 10 is connected to a transmitter transmitting impulses at such high speeds that the unit length impulses do not arrive at the receiver in operative amplitude. Amplifier 11 typifies any suitable amplifier of the received impulses and has its output circuit connected to relay LR which is a line or mixing relay. Shaping networks of the type ordinarily employed will be used in practice but are not shown.

40 Relay LR is a three-position line relay whose armature remains in a central position off of both of its contacts when no signal impulses of effective amplitude are being received. Its right hand contact is connected to positive battery and its left hand contact to negative battery. Its armature is connected by a resistance r' to point 14 on a potentiometer resistance r which is divided into four parts by points 12, 13 and 14, which may be adjustable. Point 14 is adjustably 45 connected along the middle section of potentiometer r . When the armature of relay LR is in its middle position point 13 is negative with respect to point 14 and point 12 is positive with respect to point 14. When the armature is to the left, point 50 14 is negative with respect to point 13; when the armature is to the right, point 14 is positive with respect to point 12.

Relays R₁ and PR₁ in parallel are controlled by two circuits extending from either of points 60 12 or 13 through the right or left hand contacts of relay R₂, Segments 1a, conductive brush 15, ring 16 and conductor 17 to point 14.

65 Relays R₂ and PR₂ in parallel are controlled by two circuits extending from either points 12 or 13 through the right or left hand contacts of relay R₁, conductive brush 15, segments 2a, ring 16, and conductor 17 to point 14.

70 Alternate printer magnets of a channel such as magnets 1, 2, 3, 4, 5 are connected to separate sets of distributor segments 18 and 19, each set of segments being connected by a brush to a corresponding ring of long segments, ring 20 being the long segments for short segments 18, and ring 21 being the long segments for short segments 19.

75 Dead segments are located between the live seg-

ments 18 and 19. The dead segments may be considerably shorter than a unit impulse and the live segments considerably longer thereby permitting the transmission, to the relatively slow-acting printer magnets, of a relatively long impulse, without the use of pulse lengthening tubes or other devices. In other words, the segments 18 and 19 are longer than the distance from the center of a segment 1a to the center of a next adjacent segment 2a. The impulses transmitted to the printer magnets may be made any length from shorter to longer than a unit impulse by making the live segments of suitable length. To indicate a five channel system the printer magnets of channel #1 are designated 1, 2, 3, 4, 5, of channel #2, 1¹, 2¹, 3¹, 4¹, 5¹, etc., up to 5^{IV}.

Fig. 2 discloses in curve 30 a train of transmitted impulses, in curve 40 a corresponding train of received impulses, in curve 50 the correspondingly proper movements of relay R₁, in curve 60 the correspondingly proper movements of relay R₂, and in curve 70 the impulses transmitted to the printer magnets. The time of transmission over the line is neglected and the impulses are assumed to arrive as soon as transmitted. In practice the line time is taken into account by shifting the receiving segments backward a suitable amount.

Operation of circuit of Fig. 1

30 When no signals of controlling amplitude are arriving relay LR stands in its central position and relays R₁ and R₂ stand still on opposite contacts and are maintained on opposite contacts each by the other. Relays PR₁ and PR₂ follow the corresponding relays R₁ and R₂ and likewise stand still on opposite contacts. The circuit for controlling relays R₁ and PR₁ is from point 12, of positive polarity, through right contact of relay R₂, windings of R₁ and PR₁ in parallel from right to left, segments 1a, brush 15, ring 16 and conductor 17 to point 14. The circuit for controlling relays R₂ and PR₂ is from point 13, of negative polarity, through left contact of relay R₁, windings of relays R₂ and PR₂ in parallel from left to right, segments 2a, ring 16, and conductor 17 to point 14.

35 Let it be supposed that a long positive impulse is sent from the transmitter beginning at time c . This actuates relay LR to the left which occurs at about time d . Then point 13 becomes positive with respect to point 14; this causes relay R₂ to move its armature to the left and the next impulse transmitted to the printer magnet 4 is positive instead of negative. If the transmitted impulse is but two units long as from time c to time e , the received impulse commences to die away before time e and at about time e the relay LR is released and returns its armature to its central position. Point 13 then again becomes negative with respect to point 14 and since point 13 is connected to the left hand contact of relay R₂, upon which its armature is now resting, a circuit is closed from point 13, left contact of R₂, and windings of relays R₁ and PR₁ in parallel, a segment 2a, ring 16, and conductor 17 to point 14. The negative current through windings of relays R₁ and PR₁ causes them to move their armatures to the right, whereupon R₁ and R₂ again stand in opposite positions and regenerate alternate positive and negative impulses until the line relay LR is again operated, which will happen, in the case illustrated by Fig. 2 at about time h . From curves 30, 40, 50, 60 and 70 the operation of the system for other combinations of long and

short transmitted impulses can readily be traced.

It will be noted that after any long impulse such as occurs at time *c* to *e* or *g* to *j* the relays *R*₁, *R*₂ are so positioned that the subsequent impulse or impulses of unit length to be regenerated are always in correct order.

It will be noted that the relays *R*₁ and *R*₂, together with the relays *PR*₁ and *PR*₂, comprise electromagnetic means provided with armatures for relaying impulses received from the transmission line 10 to the receiving printer magnets 1, 2, 3, etc. The relays *R*₁ and *R*₂ each is connected to control the other by means of circuit arrangements which maintain the armatures of said relays in engagement with a predetermined contact when no impulses are being received over the line in effective amplitude. The predetermined contact upon which these relays *R*₁ and *R*₂ stand is determined by the sign of the long impulse of two or more units duration last received. When the relays *R*₁ and *R*₂ remain in fixed position the impulses relayed to the printer magnets are of alternate polarity. The distributor rings 16, together with segments 1a, 2a, etc., constitute one distributor; the rings 18, 20 constitute another distributor; and the rings 19, 21 another distributor. The last two named may be arranged in a single row as shown in Fig. 4 or in two rows as shown in Fig. 1. The two-row arrangement has the advantage that the live segments to the printer magnets may be over 100% of the time duration of a unit signaling impulse as transmitted, thereby insuring that the printer magnets will be energized by an impulse of proper polarity for the full time during which the relays *PR*₁ and *PR*₂ maintain their armatures upon any given contact. There is no physical limitation upon the relationship of the distributors controlling the relays *R*₁, *R*₂, and those controlling the printer magnets except that they be synchronized and adjusted to suitable phase relation.

Description and operation of circuit of Fig. 3

45 This circuit is a modified form of that of Fig. 1 and uses a single printing relay. The corresponding parts of Fig. 1 are in light lines and identified by corresponding characters. The modified elements are designated by heavy lines 50 and comprise a printer relay *PR*_{1,2} which is connected between the armature of relay *LR* and the ring 16. Conductor 17 of Fig. 1 is omitted from Fig. 3. Relay *PR*_{1,2} follows the movements of each signal impulse whether locally regenerated 55 or incoming to the three-element line relay *LR*. Relay *PR*_{1,2} controls the printer magnets 1, 2, 3 . . . 5^{IV}, etc., to select or not in accordance with the impulse transmitted over the line.

Description of circuit of Fig. 4

60 Fig. 4 is a further modified circuit. The relays *LR*, *R*₁, *R*₂, *PR*₁ and *PR*₂ of Fig. 4 are generally the same as in Fig. 1. Relay *LR* is normally in its central position and relays *R*₁ and *R*₂ hold 65 one another on opposite contacts. The battery connections to the contacts of relay *LR* each contains a 50 ohm resistance, leads 22 and 23 each contains a 250 ohm resistance and conductor 17' extends to the mid-point of a resistance connecting 70 positive and negative battery. The contacts of relays *R*₁ and *R*₂ are each connected to battery through 500 ohm resistances. The general relation between the values of the 500 ohm and the 250 ohm resistances is essential for operation 75 although these exact values are unnecessary.

The printer magnets are divided into two groups, alternate magnets belonging to a group. All magnets of both groups are connected to a common ring 24 by brush 25' which sweeps over segments 25 connected to the several printer magnets 1, 2, 3, 4, 5, 1^I etc., up to 5^{IV}, in a five channel system, although any reasonable number of channels either even or odd may be employed. For reversing the impulses to opposite channels, the ring 24 may be split at the end of each channel and the alternate channel length segments connected to positive and negative battery respectively. Battery on the armatures of relays *PR*₁ and *PR*₂ may then be replaced by ground.

Operation of circuit of Fig. 4

When the line relay stands in neutral position, as when no line signals of controlling amplitude are arriving, relays *R*₁ and *R*₂ each holds the other in opposite positions and also hold relays *PR*₁ and *PR*₂ in opposite positions. The printer magnets will receive impulses of positive and zero polarity alternately thereby correctly reproducing the regenerated impulses. When long impulses control the line relay *LR* the one of relays *R*₁ and *R*₂ corresponding to the unit time during which the relay *LR* becomes operated is operated. This transmits correspondingly long impulses to the printer magnets. The cycle of operations indicated in Fig. 2 is equally applicable to Fig. 4.

Two features of operation require mention. When the relay *LR* operates, a pulse is delivered to the controlled magnet *R*₁ or *R*₂ stronger than that delivered when they merely hold each other in opposite position. Likewise when relay *LR* falls back to neutral position and relays *R*₁ and *R*₂ are on the same contact the next pulse delivered to move one of them is extra strong. The occurrence of these extra strong impulses at the proper times to move the relays with the occurrence of weaker impulses when they merely are to be held in position is a desirable feature of the system.

What is claimed is:

1. In a receiver of a synchronous distributor impulse transmission system of the type in which unit length impulses are regenerated and plural unit length impulses are transmitted, electromagnetic means directly controlled by the received impulses in combination with a plurality of relays functioning to regenerate and relay to a set of distributor segments unit length impulses when standing still uncontrolled by said electromagnetic means and to relay to said set of distributor segments plural unit impulses when controlled by said electromagnetic means.

2. In a system in accordance with claim 1, a pulse lengthening arrangement comprised in that the set of distributor segments are divided into a plurality of series whereby a live segment of said set may be not less than 100% of the length corresponding to a unit impulse.

3. In a telegraph system over which signaling impulses of unit length are so attenuated that they are not received in effective amplitude, regenerating relays, line electromagnetic relay means for controlling said regenerating relays in accordance with received plural unit impulses, said regenerating relays controlling each other to normally stand still to regenerate unit impulses during the time said regenerative relays are uncontrolled by said line relay means.

4. A system in accordance with claim 3 in

75

which the line electromagnetic means is a three-position relay.

5. A system in accordance with claim 3 in which said regenerating relays each controls the other through a circuit extending through a distributor and connected to contacts of said line relay means to be under the control of said line relay means.

10. In a synchronous telegraph system, an interpolating receiving circuit characterized in this that is comprises a plurality of relays individually connected with a corresponding plurality of printer rings on the receiving distributor whereby the regeneration of unit impulses of alternately opposite polarity may be effected without movement of the relay armatures.

15. In a synchronous telegraph system comprising a rotary distributor, an interpolating circuit characterized in this, that a plurality of relays are individually connected with a corresponding plurality of printer rings on the distributor, and a plurality of groups of segments for relaying alternate positive and negative impulses whenever said relays remain quiescent as the result of the 20 reception of insufficient line current to actuate them.

25. In a synchronous telegraph system comprising a rotary distributor, an interpolating circuit characterized in this, that a plurality of relays are individually connected with a corresponding plurality of printer rings on the distributor, a plurality of groups of segments for relaying alternate positive and negative impulses whenever said relays remain quiescent as the result of reception 30 of insufficient line current to actuate them, and connections whereby two successive segments (one each from two of said groups) transmit on impulses of the same polarity whenever one of said relays is actuated from one position to another by an incoming impulse of line current.

35. In a synchronous telegraph receiving system, a plurality of repeating devices adapted to supply positive and negative impulses, synchronous switching means for distributing received signal impulses to said repeating devices in rotation and for concurrently applying to each repeating device an impulse from the preceding device of such polarity as to tend to operate said device to a position opposite that of the preceding device, signal recording means, and synchronous switching means for distributing impulses repeated by said repeating devices to said signal recording means.

40. In a synchronous telegraph receiving system, a plurality of relays each having an operating winding means and an armature operable between contacts connected to opposite poles of source of potential, synchronous distributing means for distributing received signal impulses to the winding means of each relay in rotation and for concurrently applying to said winding means of each said relay an impulse from the armature of the preceding relay of such polarity and in such direction as to tend to operate the armature 45 of said relay to a position connected to a source of potential opposite that then connected to the armature of the preceding relay, signal recording means and means for connecting the armature of the relays to said signal recording means 50 in rotation.

45. In a telegraph system, a plurality of receiving magnets, electromagnetic means including armatures therefor, for transmitting impulses of reversed polarity to said magnets, a distributor, means including said distributor for operating

5. the armatures of said electromagnetic means, each electromagnetic means being under the control of the other, and means independent of said distributor for operating said armatures of said electromagnetic means in response to impulses received over a cable or signaling line.

10. In a telegraph system, a cable or signaling line over which signaling impulses are attenuated, a plurality of receiving magnets, electromagnetic means, a distributor, means including said electromagnetic means and said distributor for operating said printer magnets in accordance with the operation of said electromagnetic means, means including said distributor for operating each of said electromagnetic means under control of the other of said electromagnetic means, and means independent of said distributor for operating said electromagnetic means in accordance with impulses received over said line.

15. In a telegraph system, a signaling line over which the signaling impulses transmitted are so attenuated that the dot impulses are lost, receiving electromagnetic means including armatures, printing magnets, means including the armatures of said electromagnetic means for operating said printing magnets in accordance with the signals transmitted over said signaling line, said means including a distributor, and means together with said distributor whereby the armatures of the electromagnetic means move 20 only in response to the received impulses.

25. In a telegraph system, a signaling line, means transmitting code combinations of impulses over said signaling line, means whereby only certain of said impulses are received, a distributor, and electromagnetic means including armatures therefor for relaying all of the impulses transmitted over said signaling line to said distributor, said electromagnetic means operative to move its armatures only in response 30 to impulses actually received.

35. In a signaling system, a transmission line, means for transmitting impulses over said transmission line, printer receiving magnets, a distributor, second means together with said distributor for transmitting impulses of reverse polarity to said printer receiving magnets, while maintaining said second means in fixed position, and means independent of said distributor 40 for operating said second mentioned means in response to received impulses.

45. In a signaling system, a signaling line over which the impulses sent are so attenuated that the first portion of each impulse is not received at the receiving end, printer receiving magnets, a distributor, means together with said distributor for operating said printer magnets in accordance with said received impulses, said means being maintained normally non-operative during the transmission of dash signals while 50 repeating said dash impulses to said printer receiving magnets.

55. In a telegraph system, printer receiving magnets, electromagnetic means for transmitting impulses of reversed polarity to said printer magnets periodically, a distributor, means together with said distributor whereby said electromagnetic means controls the operation of 60 said receiving magnets while remaining non-operative.

65. In a signaling system, a transmission line over which the signaling impulses transmitted are so attenuated that the dot impulses are not received, a plurality of printer magnets, a first and a second electromagnetic means, each of 70

- said electromagnetic means being under the control of the other over circuits including a distributor, means for operating said electromagnetic means in response to impulses received over 5 said signaling line, said means being independent of said distributor, and means for operating said printer magnets, under control of said electromagnetic means, said means including said distributors.
10. 19. In a signaling system, a signaling line over which impulses transmitted are so attenuated that the impulses of dot character are not fully received, a plurality of printer magnets, a first and a second electromagnetic means, a distributor, means including said distributor for operating each of said electromagnetic means under control of the other, means including said distributor for operating said receiving magnets under the control of said electromagnetic means, 15 said printer magnet, being operated in accordance with the impulses transmitted over said signaling line, and means for operating said electromagnetic means only in accordance with the impulses received over said signaling line.
20. 20. In a telegraph system, the combination at a terminal station or a repeating station, of an incoming signaling line, electro-responsive devices, a distributor, second means together with said distributor for transmitting impulses of reverse polarity to said electro-responsive devices, while maintaining said second means in a predetermined position, and means independent of said distributor for operating said second mentioned means in response to received signal impulses.
25. 21. In a signaling system, over which the signaling impulses transmitted are so attenuated that the dot impulses are not received, printer receiving magnets and electromagnetic means including armatures therefor arranged to operate said printer magnets in accordance with said signaling impulses transmitted over said signaling line, said electromagnetic means being arranged to hold their armatures in engagement 30 with a predetermined fixed contact while operating said printer magnets in response to the dot impulses.
30. 22. In a signaling system over which the signaling impulses transmitted are so attenuated that the first portion of each impulse is not received at the receiving end, printer receiving magnets, and circuit arrangements including electromagnetic means for operating said printer magnets in accordance with the transmitted signaling impulses, said electromagnetic means being arranged to be non-operative during the transmission of the dot signals while relaying said signals to said printer magnets.
35. 23. In a signaling system, a plurality of printer receiving magnets, means for transmitting impulses of periodic reversed polarity to said printer magnets, said means being maintained in a predetermined fixed position while transmitting said impulses of reversed polarity, and means for operating said first mentioned means in response to signaling impulses transmitted over said signaling system.
40. 24. In a signaling system, a transmission line, means for transmitting signaling impulses over said transmission line, printer receiving magnets, means for transmitting impulses of reversed polarity to said printer receiving magnets while maintaining said means in fixed position and means for operating said first mentioned means 45 in response to received impulses.
45. 25. In a telegraph system, a plurality of receiving magnets, electromagnetic means including armatures therefor for transmitting impulses of reversed polarity to said receiving magnets, said armatures being maintained in engagement with their fixed contacts while transmitting said impulses and means responsive to received impulses for operating said armatures to their reversed position.
50. 26. In a telegraph system, a signaling line over which signaling impulses transmitted are so attenuated that the dot impulses are lost, receiving electromagnetic means including armatures, printer magnets, means including the armatures of said electromagnetic means for operating said printer magnets in accordance with the signals transmitted over said signaling line, and means including circuit arrangements whereby the armatures of said electromagnetic means are moved only in response to impulses received.
55. 27. In a telegraph system, means for transmitting code combinations of impulses over said signaling line, means whereby only certain of said impulses are received, and electromagnetic means including the armatures therefor for relaying all of the impulses transmitted over said signaling line, said electromagnetic means being operative to move its armatures only in response to actually received impulses.
60. 28. In a telegraph system over which signaling impulses are so attenuated that they do not operate receiving apparatus, receiver relays, repeating means for repeating impulses received over said line to said receiver relays, said means being normally non-operative while impulses are attenuated, and means including circuit arrangements whereby said first mentioned means repeats said attenuated impulses to said receiver relays.
65. 29. In a telegraph system, the combination at a terminal station or a repeating station, of an incoming transmission line, electro-responsive devices, means serving to supply impulses of reversed polarity to said electro-responsive devices while maintaining said means in a predetermined position.
70. 30. In a telegraph system, the combination at a terminal station or a repeating station, of an incoming transmission line, a plurality of electro-responsive devices, means for supplying impulses of periodic reversed polarity to said electro-responsive devices, said means being maintained in a predetermined fixed position while transmitting said impulses of reversed polarity, and means for operating said first mentioned means in response to signaling impulses transmitted over said line.
75. 31. In a telegraph system, an incoming transmission line, a plurality of receiving magnets, a pair of relays having armatures for transmitting impulses of reversed polarity to said receiving magnets, said armatures being maintained in engagement with their fixed contacts when transmitting said impulses, and means for transmitting signaling impulses received over said line in alternation to said relays.
80. 32. In a signaling system, a transmission line, a plurality of electro-responsive devices, electromagnetic means provided with armatures for relaying impulses received from said transmission line to said electro-responsive devices, means including circuit arrangements for maintaining the armatures of said electromagnetic means in engagement with a predetermined contact while no impulses are being received over said line, and means including the armatures of said electro-

magnetic means for periodically reversing the polarity of impulses to said electro-responsive devices while no impulses are being received over said line.

- 5 33. In an interpolating system, including, in combination, a receiving circuit comprising a pair of relays, recording means, and means dependent upon the operation of one of said relays to supply impulses of more than unit length and render effective two or more of said recording means.
- 10 34. In a telegraph system, the combination of a signaling line over which the shortest unit signaling impulses transmitted arrive so attenuated as not to be received in effective amplitude with a relay instrumentality connected to said line to be operated in response to longer received signaling impulses, other relays, distributor means for extending a circuit of polarity determined by the existing position of said relay instrumentality in succession to said relays, signal impulse interpreting devices, distributor means extending circuits from one or another of said other relays to said signal impulse interpreting devices, and interconnections between said other relays controlling them in such manner that said interpreting devices correctly interpret the shortest unit signaling impulses as well as the longer impulses.
- 15 35. A system in accordance with claim 34, in which the circuit extended by said relay instrumentality is operatively controlled by said relay instrumentality for a time short as compared to the time duration of a full unit signal impulse as transmitted.
- 20 36. A system in accordance with claim 34, in which the circuits extended to said impulse interpreting devices are operatively controlled by said other relays for a time duration which is long compared to the time duration of a full unit signaling impulse as transmitted.
- 25 37. A system in accordance with claim 34, in which the circuits extended to said impulse interpreting devices include active distributor segments

of length corresponding to the time duration of 100% of a full unit signaling impulse as transmitted.

38. A system in accordance with claim 34, in which the circuits extended to said impulse interpreting devices include active distributor segments of length corresponding to a time duration far over 100% of a full unit signaling impulse as transmitted.

39. In a telegraph system, a signaling line over which the signaling impulses are attenuated, a plurality of receiving magnets, electromagnetic means, a distributor, means including said electromagnetic means and said distributor for operating said receiving magnets in accordance with the operation of said electromagnetic means, means independent of said distributor for operating said electromagnetic means in accordance with received impulses, and printer magnets, said distributor being arranged to actuate the receiving magnets during substantially 50 per cent of a unit signal impulse period while permitting the transmission of impulses to the printer magnets for any desired percentage of the unit signal impulse period up to 100 per cent.

40. In a telegraph system, the combination of a terminal station or a repeating station, of an incoming transmission line, electro-responsive devices, means serving to supply impulses of reversed polarity to said electro-responsive devices while maintaining said means in a predetermined position, distributor means for limiting the effect of line impulses upon said electro-responsive devices to a time interval of short duration and means for extending on from said electro-responsive devices operating impulses of duration greater than said time intervals of short duration.

41. A system in accordance with claim 40 in which the means for extending on the impulses is circuit interrupting means for limiting the duration of the impulses.

WILLIAM A. KNOOP.
